FIG. 1 is a perspective view of an elliptical reflector for multi-LED vehicle lights, showing my new design;

FIG. 2 is a top plan view thereof;

FIG. 3 is a bottom plan view thereof;

FIG. 4 is a side elevation view thereof, the other side being identical;

FIG. 5 is an end elevation view thereof, the other side being identical; and,

FIG. 6 is a perspective view thereof, showing my new design in its position of use, it being understood that the broken line (showing the housing and lens of a vehicle lighting) is for illustrative purposes only and forms no part of the claimed design.
